Genus and species: *Calibrachoa* sp.
Variety denomination: 'KLECA16316'.

CROSS REFERENCE TO RELATED APPLICATIONS

The present application claims priority to Canadian Plant Breeder's Rights Application number 17-9143, as filed on Mar. 27, 2017. Plant Breeder's Rights for 'KLECA16316' were also applied for in Europe on Jun. 30, 2017 (Application number 2017-1692). 'KLECA16316' has not been made publicly available or sold more than one year prior to the effective filing date of this application.

BACKGROUND OF THE NEW PLANT

The present invention comprises a new and distinct variety of *Calibrachoa*, botanically known as *Calibrachoa* sp., and hereinafter referred to by the variety name 'KLECA16316'. 'KLECA16316' originated from a controlled cross conducted in Stuttgart, Germany in the summer of 2012, between the proprietary female *Calibrachoa* variety 'CA-2011-0593' (unpatented) and the proprietary male *Calibrachoa* variety 'CA-2011-0572' (unpatented).

The seeds were sown and plants were grown for evaluation. A plant was selected in May 2012 which had dark purple flowers and was subsequently named 'KLECA16316'. In May 2012, 'KLECA16316' was first

2

vegetatively propagated by tip cuttings in Stuttgart, Germany. 'KLECA16316' was found to reproduce true to type in successive generations of asexual propagation via tip cuttings.

SUMMARY

The following are the most outstanding and distinguishing characteristics of this new variety when grown under normal horticultural practices in Stuttgart, Germany.

1. Dark purple colored flowers; and
2. A semi-upright and vigorous plant habit.

DESCRIPTION OF THE PHOTOGRAPH

This new *Calibrachoa* plant is illustrated by the accompanying photograph which shows the flowers and foliage of the plant. The photograph is of an eight-week-old plant grown in a greenhouse in Stuttgart, Germany in May 2014. The colors shown are as true as can be reasonably obtained by conventional photographic procedures.

DESCRIPTION OF THE NEW VARIETY

The following detailed descriptions set forth the distinctive characteristics of 'KLECA16316'. The data which define these characteristics were collected from asexual reproductions carried out in Stuttgart, Germany. Data was

collected on 20 week old plants grown outdoors in Stuttgart, Germany in June 2017. Color references are to The R.H.S. Colour Chart of The Royal Horticultural Society of London (R.H.S.), 5th edition (2007).
